GAME DEVICE

George E. Von Berg, New York, N. Y.

Application January 8, 1940, Serial No. 312,903

4 Claims. (Cl. 273—142)

My invention relates to game devices and has particular reference to chance game devices employing symbols, such as are usually provided on dice cubes, etc.

My invention has for its object to provide a device which can be manually operated for bringing into view different combinations of symbols, numbers, etc., the appearance of such symbols and their combinations being controlled entirely by chance.

My device is particularly adapted for use as an ordinary dice game, for which purpose I provide it with two wheels, each wheel carrying dice symbols in the form of dots from 1 to 6. I provide a suitable casing for the wheels and a simple spring mechanism whereby both wheels are set in rotation when the spring mechanism is manually moved. The engagement between the spring mechanism and the wheels is of such nature that the wheels are given rotation when the spring device is moved in one direction and continue to rotate freely as long as the spring device is depressed, being stopped when the spring device is released, at which time a positioning feature comes into action for stopping the wheels with the symbols exactly registering with the corresponding windows in the casing, through which the symbols may be observed.

Other objects and advantages of my invention will be evident from a perusal of the accompanying specification and drawing, in which:

Fig. 1 is a plan view of my device with the cover removed;

Fig. 2 is a sectional view taken on the line 2—2 of Fig. 1;

Fig. 3 is an outside front view of my device;

Fig. 4 is a top view of the same;

Fig. 5 is a front plan view of a modified device partly in section;

Fig. 6 is a detail view of a rotary disc showing its under side; and

Fig. 7 is a detail view of a handle.

My game device consists of a casing having a base portion 1 and a cover portion 2. It may be made of any suitable material such as metal, glass, molded compound, etc. The two casing portions are joined together as by bosses 3 fitted tightly in holes 3'. The casing base 1 has projections 4 with holes or bearings for shafts 5, the other ends of the shafts abutting the inner side of the cover 2. Discs 6 are provided with central bushings 7 rotatively mounted on the shafts 5. The discs are further provided with teeth 8, which are engaged by suitably formed projecting portions or loops 9 of a spring 10. The spring

may be formed of a single piece of wire with a bridge 11 on top having a U-shaped loop 12 imbedded in a handle 13. The latter, as shown in Fig. 7, may be made of two flat pieces with grooves 14 for the wire loop 12, the pieces being joined together in any suitable manner, as by use of a suitable cement, screws, etc. The spring 10 has curved legs 15 slidably fitted in grooves 16 formed at the joint of the casing base 1 with the cover 2. The legs 15 urge the spring upward, 10 pressing the bridge 11 against the inner side of the casing wall as shown in Fig. 1, with the handle 13 extending through a corresponding slot between the casing base and the cover.

In this position of the spring, the loops 9 are forced into spaces between consecutive teeth 8, thereby preventing rotation of the discs. The discs are provided with symbols 16, preferably in the form of dice markings as indicated by dots or perforations, each symbol comprising from one to six perforations, as shown, the symbols being equally spaced on the discs.

The number of teeth 8 corresponds to the number of the symbols 16, each symbol being located centrally between the two consecutive teeth. The cover has windows 17, one for each wheel, so positioned that when the discs are held by the spring 10, one symbol on each wheel is positioned exactly opposite the window, as shown in Fig. 3.

The spring 10 can be depressed downward by applying pressure to the handle 13 against the resilient resistance of the legs 15, thereby causing the discs to spin on the shafts 5. The loops 9, when the spring is fully depressed, leave entirely the teeth 8, permitting free rotation of the discs while the spring is so depressed. Upon release of the spring it returns by its resiliency to the original position shown in Fig. 1, with the loops 9 engaging each a pair of the teeth 8, thereby so positioning the discs that one of the symbols registers with the corresponding window 17.

A modified device is shown in Fig. 5, its casing 18 having a plurality of pairs of wheels 6 mounted for rotation in the same manner as described in connection with Fig. 1. Each pair of discs is engaged by the loops 9 on springs 19, the latter having inverted U-shaped loops 20 engaged by hooks or clips 21 attached to an operating bar 22. The bar extends to the upper end of the casing and has a handle 23, the lower end 24 having a retrieving spring 25. The cover 26 of the casing has windows 17 for each pair of discs.

The windows may be closed by the covers 27 sliding between guides 28. Additional windows 55

29 may be provided in the casing opposite the front windows 17 for admitting light through the perforations which form symbols 16. The light passing through the perforations may be colored differently for different discs by attaching colored, translucent films 30 to the rear side of the discs, as shown in Fig. 6.

5 The teeth 8 may be cast or molded integrally with the discs or if the discs are made of metal, 10 the teeth may be punched out of the metal of the discs and bent outward as shown in Fig. 6.

It is understood that my game device may be further modified without departing from the spirit of the invention as set forth in the appended claims.

15 I claim as my invention:

1. A game device comprising a casing, a pair of discs rotatively supported in the casing in the same plane at a distance from each other and provided with game symbols on their front sides, 20 the casing having one opening for each disc for observing the symbols, each opening being adapted to expose one symbol, teeth on the sides of the discs, a member movably supported in the

25 casing between the discs comprising two legs extending alongside each disc joined together at the top, a handle extending from the joint between the legs to the outside of the casing, resilient extensions on the lower end of the legs 30 resting against the inner wall of the casing and urging the member upward so as to expose the handle, projections at the sides of the legs adapted to engage the teeth for holding the discs stationary when the member is in its neutral position with the handle extending outward and one symbol exposed in each opening, the projections being adapted to cause rotation of the discs when the member is moved by depressing the handle, the teeth being disengaged from the projections

35 at the end of the downward movement of the member, thereby permitting free rotation of the discs, the projections being adapted to reengage the teeth when the member is released and returned into the neutral position by the resilient extensions.

40 2. A game device comprising a casing having a base and cover portions joined together, a pair of discs rotatively supported in the casing in the same plane at a distance from each other and provided with a plurality of game symbols equally spaced from each other, the cover portion having one opening for each wheel, each opening being adapted to register with one of the symbols, teeth on the discs, a spring movably supported in the casing between the two wheels, the spring having portions adapted to engage the teeth on the discs for retaining the discs stationary, a handle on the spring extending outside of the casing, extensions on the spring engaging the casing inside and resiliently urging the handle outward, the spring, when being depressed by the handle, being adapted during the first portion of this movement to spin the discs, and to become disengaged from the discs at the end of its movement, thereby allowing free rotation of the discs,

45 the spring, when released, being adapted to re-engage the teeth of the discs by its projecting portions, thereby stopping the discs.

3. A game device comprising a casing, a pair of discs rotatively supported in the casing in the same plane at a distance from each other and provided with game symbols on their front sides, 5 the casing having one opening for each disc for observing the symbols, each opening being adapted to expose one symbol, teeth on the sides 10 of the discs, a member movably supported in the casing between the discs formed of a piece of resilient wire bent at the middle so as to form two legs extending at the sides of the discs, a handle on the wire extending from its middle portion 15 to the outside of the casing, the ends of the legs being curved outward, resting against the inner side of the casing so as to urge the legs upward with the handle fully extending outside the casing, the legs being provided with loops in the 20 form of tapering projections adapted to engage the teeth, thereby retaining the discs stationary with one symbol showing in each opening, the projections being adapted to cause rotation of the discs when the handle is depressed and being 25 further adapted to release the teeth at the end of the movement of the handle, thereby permitting free spinning of the discs, the projections being adapted to re-engage the teeth when the handle is released and the legs with the projections 30 are returned into the upward neutral position by the resilient leg extensions.

4. A game device comprising a casing, a pair of discs rotatively supported in the casing in the same plane at a distance from each other and 35 provided with game symbols on their front sides, the casing having one opening for each disc for observing the symbols, each opening being adapted to expose one symbol, teeth on the sides of the discs, a member movably supported in the 40 casing between the discs, a handle on the member extending to the outside of the casing, springs at the sides of the member having curved portions adapted to engage the teeth and adapted to hold the discs stationary when the member is 45 in the neutral position with one of the symbols fully exposed in each opening, the springs being adapted to resiliently move toward each other when passing over the teeth and being adapted to hold the discs stationary when the member is 50 in its neutral position with the handle extending outward and with the projections engaging the teeth, exposing one symbol in each opening, the 55 projections being adapted to cause rotation of the discs when the member is moved by depressing the handle, the teeth being adapted to be released at the end of the movement of the member, thereby permitting free rotation of the discs, resilient extensions on the springs engaging the casing inside and urging the handle outward, the 60 projections being adapted to re-engage the teeth, thereby stopping the rotation when the handle is released and the member is returned into the 65 neutral position by the resilient extensions.
